(57) **CLAIM**

The ornamental design for a single kink fishing hook, as shown and described.

DESCRIPTION

FIG. 1 is a perspective view of a first embodiment of a single kink fishing hook having a barb and a shank with an eyelet, shown in broken lines, in which a retention kink is adjacent to the front length and/or tip of the hook.

FIG. 2 is a front view of the single kink fishing hook of FIG. 1.

FIG. 3 is a first side view of the single kink fishing hook of FIG. 1.

FIG. 4 is a second, opposite side view of the single kink fishing hook of FIG. 1.

FIG. 5 is a top view of the single kink fishing hook of FIG. 1.

FIG. 6 is a bottom view of the single kink fishing hook of FIG. 1.

FIG. 7 is a perspective view of a second embodiment of a single kink fishing hook having a barb and a shank with an eyelet, shown in broken lines, in which a retention kink is adjacent to the front length and/or tip of the hook.

FIG. 8 is a front view of the single kink fishing hook of FIG. 7.

FIG. 9 is a first side view of the single kink fishing hook of FIG. 7.

FIG. 10 is a second, opposite side view of the single kink fishing hook of FIG. 7.

FIG. 11 is a top view of the single kink fishing hook of FIG. 7.

FIG. 12 is a bottom view of the single kink fishing hook of FIG. 7.

FIG. 13 is a perspective view of a third embodiment of a single kink fishing hook having a barb and a shank with an eyelet, shown in broken lines, in which a retention kink is adjacent to the front length and/or tip of the hook.

FIG. 14 is front view of the single kink fishing hook of FIG. 13.

FIG. 15 is a first side view of the single kink fishing hook of FIG. 13.

FIG. 16 is a second, opposite side view of the single kink fishing hook of FIG. 13.

FIG. 17 is a top view of the single kink fishing hook of FIG. 13; and,

FIG. 18 is a bottom view of the single kink fishing hook of FIG. 13.

The broken line showing of environment in the drawings is included for the purpose of illustrating only and forms no part of the claimed design.
